UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed February 27, 1922. Serial No. 539,710.

To all whom it may concern:

Be it known that I, CHARLES DAVID BONSALL, a citizen of the United States, and a resident of the city of Pittsburgh, in the 5 county of Allegheny and State of Pennsylvania, have invented a certain new and useful Improvement in Car Roofs, of which the following is a specification.

My invention relates to car roofs of the 10 type wherein the roofing sheets extend from side plate to side plate of the car and are riveted thereto and to each other to form a rigid load sustaining structure.

Heretofore the side marginal portions of 15 such sheets have been formed into ribs designed to act after the manner of car lines to increase the load carrying capacity of the roof and serve as frame members to brace and stiffen the car-body; but such designs 20 have usually been developed with a view to adapting each rib to take care of the same stresses in the same way as the other ribs, so that such designs would vary in accordance with the importance that the designer 25 assigned to the various stresses that were expected to act thereon in practical use.

The principal object of the present invention is to produce a roof that will be stiffer and stronger than previous roofings of the 30 same weight of metal; and the invention consists principally in forming the ribs in two or more types arranged alternately and separately designed to better fit them for taking care of contemplated stresses. The invention also consists in the parts and the 35 arrangements and combinations of parts hereinafter described and claimed.

In the accompanying drawing, wherein like symbols refer to like numbers wherever 40 they occur,

Fig. 1 is a plan view of a portion of a car roof embodying my invention;

Fig. 2 is an enlarged transverse section 45 through one half of the roof on the line 2—2 in Fig. 1;

Fig. 3 is a longitudinal section along the ridge line of the roof on the line 3—3 in Fig. 1;

Fig. 4 is similar section midway of the 50 ridge and eaves on the line 4—4 in Fig. 1; and

Fig. 5 is a similar section adjacent to the side plate on the line 5—5 in Fig. 1.

The present roof comprises heavy gage

roof sheets 6 that extend from side plate 7 to side plate 7 of the car and are suitably secured thereto by rivets 8. The side margin of each sheet is pressed up and riveted to a similar margin of the next adjacent sheet to form hollow ribs that extend from side plate to side plate. The hollow ribs are of two types, the ribs of one type alternating with those of the other type and the ribs of both types varying in width from ridge to eaves. The ribs of the type A have a minimum width at the ridge and widen gradually to the eaves; whereas the ribs of type B are widest at the ridge and gradually decrease in width to the eaves. As illustrated in the accompanying drawing, the ribs of both types are of uniform depth from ridge to points adjacent to the eaves where they merge abruptly into the plane of the roof; but, if desired, the depth of said ribs may be gradually decreased from ridge to eaves.

One side marginal portion of each roof sheet is pressed up preferably in the form of a seam flange 9 of substantially inverted L-shaped section; that is, said marginal portion has a nearly vertical web portion at the top of which is a horizontal flange. The other side marginal portion of said sheet is pressed up preferably in the form of a seam flange 10 of inverted channel shaped section; that is, it comprises a nearly vertical web portion, a horizontal portion that forms the top of the rib and a downward portion that forms the side of the rib. The L-shaped flange 9 at one side 80 margin of each sheet widens from ridge to eaves and the channel shaped flange 10 at the opposite side margin of said sheet decreases in width from ridge to eaves.

The roof sheets are provided at their eaves ends with depending drip flanges 11, which overhang the outer edges of the side plates 7; and the seam flanges 9 and 10 of said sheets are curved downwardly near their eaves ends and merge into the plane of the body of the sheets at points where the eaves flanges 11 are turned downwardly. The reverse taper of the seam flanges 9 and 10 at the side margins of the sheets permits the use of a sheet blank having parallel sides, thereby eliminating the expense of shearing the sheet to a special shape before pressing; and the horizontal flanges 12 and

13 that appear in the eaves sections of said seam flanges 9 and 10 is the surplus of metal resulting from the downwardly curved ends of said flanges. Thus, the inverted 5 L-shaped flange 9 at one side margin of a sheet has an eaves portion of inverted channel-shaped section whose outer flange is turned outwardly up the plane of the body of the sheet to form the lateral flange 10 12; and the eaves portion of the depending outer margin of the inverted channel-shaped flange 10 at the opposite margin of said sheet is also turned outwardly in the plane of said sheet to form the lateral 15 flange 13.

The sheets are assembled by lapping the L-shaped flange 9 of one sheet over the corresponding tapered channel-shaped flange 10 of an adjacent sheet, thereby forming a 20 roof having a series of type A ribs, which widen from ridge to eaves, alternating with type B ribs, which decrease in width from ridge to eaves. The horizontal portions of the lapped seam flanges are rigidly secured 25 together by rivets 14, and the lateral flanges 12 and 14 at the eaves ends of said lapped flanges are rigidly secured to the body portions of adjacent sheets by means of the rivets 8 that secure the eaves ends of the 30 sheets to the side plates 7.

Running boards 15 are arranged lengthwise of the car at the ridge and are securely bolted to the upwardly offset flanges of metal running board saddles 16. The running board saddles rest on and are riveted to the lapped seam flanges by means of the rivets 14 that secure said flanges together.

The type A ribs are designed to accomplish the various functions of a carline or carline rib with a special importance attached to the function of taking care of those stresses that tend to rack and twist the car-body and distort it endwise; whereas the type B ribs are designed with especial reference to increasing the vertical carrying capacity of the roof. It is noted that by alternating such ribs, the roof as a whole is stronger than a roof with uniform ribs each designed to take care of the 50 same stresses. This is particularly true because all the ribs are adapted to take care to some extent of all of the several stresses and because the ribs are close enough together to prevent any undue concentration 55 of stresses at any one point. Also, the roof is of more uniform strength for the reason that for all longitudinal vertical sections through the roof, the cross-sectional area of the metal is the same.

60 It is noted that the blank sheets, from which my roof is made, may be of rectangular shape and that such rectangular blanks may be pressed up, without any trimming thereof, to adapt their side margins for cooperation with adjacent sheets in

forming the hollow ribs above mentioned. As illustrated in the drawing, one margin of a sheet is adapted to cooperate in forming a hollow rib of type A, while the opposite margin of the same sheet is adapted to 70 cooperate in forming a rib of type B.

Obviously my invention admits of considerable modification in the designs of the 75 seams or ribs and I do not wish to be limited to the specific designs illustrated. For instance, both seam flanges of a sheet may be of the same cross-sectional shape. Likewise, while the drawing illustrates the invention as embodied in a roof wherein ribs of two types alternate, it is obvious that 80 the alternation might be of a rib of one type with two or more ribs of another type.

What I claim is:

1. A metal car roof comprising a series of transverse stiffening ribs whose width varies 85 from ridge to eaves, some of said ribs being wider at the eaves than at the ridge and other of said ribs being wider at the ridge than at the eaves.

2. A metal car roof comprising a series of transverse stiffening ribs of greater width 90 at the ridge than at the eaves alternating with other transverse stiffening ribs of greater width at the eaves than at the ridge.

3. A car roof comprising a plurality of 95 metal roof sheets connected along their side margins by raised seams, some of said seams tapering in width from ridge to eaves and other of said seams tapering in width from eaves to ridge.

4. A car roof comprising transversely arranged metal roof sheets having their side margins connected together to form raised 100 seams of varying width from ridge to eaves, said seams tapering in reverse directions and alternating one with the other.

5. A car roof comprising a plurality of roof sheets having stiffening ribs extending longitudinally of the sheets and of greater width at the ridge than at the eaves.

6. A car roof comprising a plurality of roof sheets whose side margins are connected together to form seams, said seams being of greater width at the ridge than at the eaves.

7. A metal car roof comprising a series of transverse stiffening ribs of gradually increasing width from ridge to eaves alternating with stiffening ribs of gradually increasing width from eaves to ridge, the cross-sectional area of the metal being substantially the same for all longitudinal sections through the roof.

8. A roof sheet for a car roof, said sheet having a flange at one side margin which increases in width from ridge to eaves and a flange at its opposite side margin which increases in width from eaves to ridge.

9. A roof sheet having at each of its side margins an offset seam flange of gradually varying width, the width of one side flange

at the ridge being substantially the same as the width of the opposite marginal flange at the eaves.

10. A roof sheet having seam flanges along its side margins adapted to interlock with the seam flanges of a similar sheet to form seams, the seam flange at one side margin of a sheet being of substantially inverted L-shaped section and the seam flange at the 10 opposite side margin of said sheet being of substantially inverted channel-shaped section.

11. A roof sheet for a car roof, said sheet having seam flanges along its side margins 15 adapted to interlock with the seam flanges of a similar sheet to form seams, the seam flange at one side margin of a sheet being of substantially inverted L-shaped section and the seam flange at the opposite side margin 20 of said sheet being of substantially inverted channel-shaped section, one of said flanges being wider at the eaves than at the ridge and the other of said flanges being wider at the ridge than at the eaves.

25 12. A car roof comprising a plurality of metal roof sheets whose side margins are connected together to form raised seams

which vary in cross-sectional area from ridge to eaves, some of said seams increasing in cross-sectional area from ridge to eaves 30 and other of said seams decreasing in cross-sectional area from ridge to eaves.

13. A metal car roof comprising a series of transverse stiffening ribs whose cross-sectional area varies from ridge to eaves, some 35 of said ribs increasing in cross-sectional area from ridge to eaves and other of said ribs decreasing in cross-sectional area from ridge to eaves.

14. A car roof comprising a plurality of 40 metal roof sheets having their side margins connected together to form raised seams of greater cross-sectional area at the eaves than at the ridge alternating with other seams of greater cross-sectional area at the ridge than 45 at the eaves.

15. A car roof comprising a plurality of 50 metal roof sheets having transverse stiffening ribs of greater width and cross-sectional area at the ridge than at the eaves.

Signed at Parnassus, Pa., this 23rd day of February, 1922.

CHARLES DAVID BONSALL.
